UNITED STATES PATENT OFFICE.

JOSEPH COVELESKIE, OF WILKES-BARRE, PENNSYLVANIA.

KNOT-TYING MECHANISM FOR USE IN WARP-TYING.

Application filed August 1, 1923. Serial No. 655,116.

To all whom it may concern:

Be it known that JOSEPH COVELESKIE, a citizen of the United States, residing at Wilkes-Barre, in the county of Luzerne and State of Pennsylvania, has invented certain new and useful Improvements in Knot-Tying Mechanisms for Use in Warp-Tying, of which the following is a specification.

The invention relates to a knot-tying mechanism, particularly designed for use in a warp-tying mechanism for silk, wool, cotton and other wiry yarns, though the broad principles of the invention may be employed in any knotting device, as for example, in connection with a grain binder or the like.

An important object of the invention is to provide a smoothly operating device of this character, which may be manufactured at a relatively low cost and which has comparatively few parts to get out of order.

The present invention is concerned only with the knotting and cutting mechanism, the connections which adapt it for use with any special machinery not being shown in detail in the drawings, and not being claimed in the present application. A slack and tension cam, the general function of which is well understood in the art is shown herewith, but is not claimed specifically in the present application as other such devices performing the same well-known function may be substituted, or if desired, the slack and tension cam may be omitted, as the device is operative without this mechanism, though its presence adds to the mechanical perfection of the device.

More specifically the knot-tying mechanism includes a pair of rotating arches or like members, about which the threads to be knotted are looped, means for reciprocating the arches so as to release the thread at the proper instant, and a hook reciprocable intermediate the arches which is adapted to engage the waste ends of the thread and draw the same through the loop at the instant the arches are withdrawn, thereby forming a knot in the threads. The invention further relates to a novel means for cutting off the loose ends of the thread, at instant the knot is formed, said means comprising a fixed knife which extends transversely through a slot formed in the end of the reciprocating hook, whereby when the hook is withdrawn for knotting the

thread the ends of the thread are brought into contact with the knife, thereby severing the waste ends of the thread.

Other important objects will appear hereinafter by reference to the following detailed description and accompanying drawings in which is shown an illustrative embodiment of the invention.

Fig. 1 is a side elevation of the whole mechanism, some of the parts being shown in central vertical section.

Fig. 2 is a central horizontal section of the same, some parts being shown in plan.

Figs. 3 to 10 are diagrammatic views showing successive steps of the tying operation.

Fig. 11 is a view showing the simple form of knot formed.

Fig. 12 is an enlarged detail view on line 12-12 of Fig. 2, showing the thread cutting knife in its relation to the split hook and the reciprocating arches.

The knot tying mechanism is designed for uniting the ends of threads from the warp and thrum. Previous devices of this character have been unsuitable for uniting very fine silk-threads, have been cumbersome in operation, and frequently break the threads which are to be united. The present invention overcomes the defects of these earlier machines and is simple in operation and very inexpensive to manufacture. The showing of the device is somewhat diagrammatic, and many details may be varied without departing from the spirit of the invention.

Referring particularly to Figs. 3 to 10, the reference numeral 1 denotes the thread guide which holds the threads from the warp and thrum, which are to be united. The loose ends of the thread are held by a thread distributing machine (not shown) of any known construction, and the slack in the thread is taken up by a slack and tension cam 2, the threads passing beneath the thread positioning guard 3. The parts referred to above are well known in the art, and taken broadly comprise no part of the present invention except in combination with other features of the invention, and may be varied without departing from the essential features of the invention as claimed in the present application.

The novel features of the invention which

are the subject of this application are the thread looping, knotting and cutting mechanism, which will now be described in detail for the purpose of illustration, though it is to be understood that the broad features of the invention are not limited to such details. The thread is knotted by means of thread looping elements 4 in the form of wire arches which are carried by a rotating and reciprocating disc 5 (Fig. 10) slidable upon a shaft 6. Acting in conjunction with the looping elements 4 is a split hook 7 likewise slidable upon and guided by the shaft 6, and carried by a second rotatable and reciprocating disc 8. The shaft 6 is driven from any suitable source of power and carries at its outer end a rotating table 9 which carries the knot-tying device and is provided with a boss 10 having an aperture for passing the split hook 7. The table 9 is also apertured to pass the wire arches 4 and carries a knife 11, in conjunction with which the split hook operates, for cutting off the loose ends of the threads after the knot has been tied (see Fig. 12).

The boss 10 as clearly shown in Figs. 1, 4 and 10, is rounded on top and is located somewhat away from the central axis of the plate 9 as shown for example in Figs. 2 and 3. It will also be noted that the wire arches are located at opposite sides of the boss 10 and that the hook 7 reciprocates back and forth through the central aperture in the boss. As shown in Figs. 3 and 9 the knife 11 is located just opposite the boss 10, on the other side of the table 9, and extends transversely of the aperture in the boss. As shown in Figs. 3, 9 and 12, the end of the hook 7 is split to pass the knife 11 so that as the hook is withdrawn through the aperture in the boss, the ends of the threads which are carried by the hook will be drawn across the knife 11 and severed.

A longitudinally movable lifting fork 12 is provided for guiding the thread upon the wire arches for forming the half hitch. This fork also places the thread in the hook at the proper moment for forming the half hitch.

As shown in Fig. 3, the threads are in position for tying, being firmly held between the thread guide 1 and the slack and tension cam 2. The wire arches 4 are now rotated to the position shown in Fig. 4 and the thread guided on the loops by means of the lifting fork 12. Further operation of the device brings the parts successively to the positions shown in Figs. 5, and 6. A complete loop has now been formed in the threads which are next ready for tying. In Fig. 7 the lifting fork is shown advanced for placing the threads in the hook which has now moved forward through the apertures in the rotating table 9 and base 10. In Fig. 8 the hook has been retracted draw-

ing with it the thread ends through the thread loop. Further retraction of the hook to the position shown in Fig. 9 results in knotting the threads to be tied and cutting off the loose ends. The knot formed is the simple single knot, shown in Fig. 11.

It will be noted that in the position shown in Fig. 8, wherein the hook 7 has first been retracted, drawing with it the waste ends of the threads; the wire arches 4 have also been withdrawn slightly, thus bringing the thread loop into contact with the rounded portion of the boss 10. In the next position as shown in Fig. 9, the arches have been withdrawn below the level of the boss 10 and the thread loop, under the tensioning action of the slack and tension cam 2, slips over the rounded portion of the boss and tightens around the loose ends of the thread, which ends have been drawn through the loop by the hook 7 in the operation shown in Fig. 8. When the ends of the thread are withdrawn by the hook 7 sufficiently, they engage the knife 11 which severs the waste ends. In the position shown in Fig. 10, waste ends have been severed and are carried away by a hook formed in the end of the slack and tension arm as shown in Figs. 1 and 10.

The various operations of the slack and tension cam 2 and the relative movement of its thread engaging surface with respect to the fixed thread positioning guard 3 is of course due to the peculiar shape of the cam 2 which is eccentrically mounted on the rotating shaft 30 as shown in Figs. 1 and 2. The cam is so shaped and its speed so regulated that the proper tension is exerted upon the thread ends at each successive operation. I do not limit myself to any particular shape or speed of rotation as these are factors which may be experimentally determined in any particular case, and according to well recognized principles.

The essential features of the invention have been described and any desired means for automatically operating the cooperating parts of the knotting mechanism may be employed.

As shown in Figs. 1 and 2, the gearing for operating the knot tying mechanism is mounted in a casing 12 through which extends a main drive shaft 14 having a gear 15 at one end, rotated from any suitable source of power. The shaft carries a cam cylinder 16, having cam grooves 17, and 18 formed therein, for reciprocating the discs carrying the split hook and wire arches respectively.

Cooperating with the grooves 17 and 18 are cam rollers 21 and 22 carried upon shafts 23 and 24. The shaft 23 carries a hand 25, which grasps the hook operating disk 8. The lifting fork 12 is also carried by the hand 25 and consequently recipro-

cates at the same rate as the split hook. The shaft 24 carries a similar hand 26 which grasps the arch carrying disc 5.

The drive shaft 14 carries also a gear 19 which meshes with a gear 20 keyed upon the shaft 6 which carries the rotating table 9. The discs 5 and 8 are rotated with the table 9 by means of an eccentric rod 28 carried by the table and passing eccentrically through the discs 5 and 8. A link 29 connects this rod to the shaft 6.

The slack and tension cam 2 is also operated from the main drive shaft through a shaft 30 having at its end a bevel gear 31 which engages a bevel gear 32 mounted on the end of the shaft 14.

The various parts of this device have been described in great detail for the purpose of illustration, but it is understood that many changes may be made without departing from the spirit of the invention which is to be limited only by the claims.

For example, while I prefer to use wire arches, such as are shown in the drawing, I may, if desired, substitute other rotating and reciprocating loop forming members.

What I claim:—

1. In a knot-tying mechanism, in combination, a rotating disc or table, a pair of spaced loop-forming members extending through said table, means for reciprocating said loop-forming members, a hook reciprocating intermediate said loop-forming members, and means for reciprocating said hook in timed relation to said loop-forming members.

2. A combination thread tying and cutting mechanism comprising means for forming a loop in the thread, a reciprocating hook adapted to draw the waste ends of the thread through the loop for tying the same, and a thread cutting knife extending transversely through the hook but not reciprocable therewith, whereby when the hook is retracted for tying the knot the ends of the thread are brought in contact with said knife and severed.

3. A combined knot tying and waste-end cutting mechanism for threads and the like, comprising means for forming a loop intermediate the ends of the threads, a reciprocating split hook adapted to draw the waste ends of the thread through the loop to form a knot, and a knife extending transversely through the split hook but not reciprocable therewith, whereby when the knot is formed the waste ends of the threads are simultaneously cut off in the same operation.

4. In a device of the character described, in combination, a pair of threads supported between fixed members, a slack and tension cam adapted to engage said threads intermediate the fixed members for regulating the tension thereof, and a knot-tying mechanism intermediate said cam and one of the fixed members, comprising a pair of spaced arches adapted to engage the threads, means for rotating said arches for forming a loop in said threads, a hook mounted intermediate the arches and adapted to engage the threads beyond the loop, means for reciprocating said hook for drawing the ends of the thread through said loop, and means for reciprocating said arches.

5. In a knot-tying mechanism, in combination, a rotating table, a pair of spaced loop forming members extending through said table, a boss on said table intermediate the arches and having a central aperture, a split, reciprocating, knot forming hook adapted to be projected or retracted through said aperture, and a thread cutting knife secured to said table transversely of said aperture, on the face of said table opposite said boss, and extending transversely through said hook, means for supporting a pair of threads within the path of said loop forming members and knot forming hook, and means for adjusting the tension of said threads according to the operation being performed.

In testimony whereof I affix my signature.

JOSEPH COVELESKIE.
